CLAIM

The ornamental design for a bottle, as shown and described.

DESCRIPTION

FIG. 1 is a perspective view of a bottle from the upper right, with the label and caps removed, illustrating my new design;

FIG. 2 is an upside down perspective view thereof;

FIG. 3 is a front perspective view thereof;

FIG. 4 is a perspective view of the bottle laid on its back;

FIG. 5 is a top perspective view thereof;

FIG. 6 is a front elevational view thereof with a label attached to the bottle;

FIG. 7 is a top perspective view thereof from the left and closed by caps;

FIG. 8 is a front perspective view thereof;

FIG. 9 is a perspective view of the bottle laid on its back; and,

FIG. 10 is a side perspective view thereof.
